UNITED STATES PATENT OFFICE.

HOMER S. ROGERS, OF MILWAUKEE, WISCONSIN, ASSIGNOR TO MILWAUKEE AIR POWER PUMP COMPANY, OF MILWAUKEE, WISCONSIN, A CORPORATION OF WISCONSIN.

PNEUMATIC PUMP.

Application filed February 20, 1922. Serial No. 537,806.

This invention relates to pneumatic pumps and the object of the invention is to improve the construction and operation of pneumatic pumps in the manner to be hereinafter described and claimed.

Referring to the drawing which accompanies this specification and forms a part hereof, which drawing illustrates an embodiment of this invention, the figure of the drawing illustrates a vertical section of a pneumatic pump.

Referring to the drawing, the reference numerals 1 and 2 designate pump chambers which may be constructed in any suitable manner. The drawing illustrates the pump chambers as of different sizes merely to show a compact arrangement of parts for a small-bore well, as equality or inequality of size of the pump chambers has nothing to do with the principle of operation of the pump. The pump chambers are provided with inlet water valves 3 and 4, illustrated as gravity check-valves, and water outlet valves 5 and 6, illustrated as spring-backed check-valves, and the principle of operation of these valves is the principle of an ordinary check-valve which opens to permit fluid to pass in one direction and closes to prevent the passage of the fluid in the opposite direction. The pump, when in use, is submerged in water, and the compressed air forces the water from the pump chambers through a water discharge pipe 7 to the place desired. Compressed air may be conducted to the pump in any suitable manner, as by a pipe 8 for example, and is admitted to the pump chamber 1 only when the compressed air valve 9 is open, and is admitted to the pump chamber 2 only when the compressed air valve 10 is open. The compressed air valves 9 and 10 will be referred to as air admission valves. The pump chamber 1 is provided with an air exhaust port 11 adapted to be closed or opened by an air exhaust valve 12, and the pump chamber 2 is provided with an air exhaust port 13 adapted to be closed or opened by an air exhaust valve 14. The air admission valves 9 and 10 are illustrated as poppet valves provided with springs 15 and 16 tending to close them with the pressure, or, in other words, in the direction of the flow of the compressed air. The air admission valves will, consequently, always remain closed unless opened and retained opened by some mechanism. The

poppet type of valve is a simple construction and an overthrow of its opening movement does not tend to restrict the passageway for the flow of fluid so that it lends itself admirably to situations where close adjustments are to be avoided. In the construction illustrated by the drawing, the air exhaust valves 12 and 14 are movable horizontally and are connected by a rod 17 so that as one is closed the other is opened. Any suitable means may be employed for guiding these valves, as for example guides 18 and 18, and a light spring 19 may be used to keep the air exhaust valve 12 closed, the air exhaust valve 14 open, and the air admission valve 9 open when the pump is not under compressed air. Under such a condition the spring 16 will keep the air admission valve 10 closed so that these valves cannot occupy indefinite or indeterminate positions when the pump is not under compressed air. The result is that the pump will always start operating, if submerged, when the compressed air is admitted to the pipe 8. The tension or power exerted by the springs 15 and 16 need not be of any particular amount except that, with the specific construction shown, the spring 19 should be sufficiently powerful to compress the spring 15, and the combined tensions of the springs 16 and 19 and the air pressure on the air admission valve 10, when closed, should be less than the power which can be exerted by a motor mechanism to be described.

Tripping mechanism is employed to open the air admission valves 9 and 10 while the air exhaust valves 12 and 14 are being moved and a very simple and efficient construction is shown by the drawing consisting of the bell-crank levers 20 and 21 pivoted to ears 22 and 23. One arm of the bell-crank lever 20 engages in a recess 24 in the air exhaust valve 12 and the other arm extends under a stem 25 projecting downwardly from the air admission valve 9. In a similar operating manner one arm of the bell-crank lever 21 engages in a recess 26 in the air exhaust valve 14 and its other arm extends under a stem 27 projecting downwardly from the air admission valve 10. The principle of the construction is that the bell-crank levers 20 and 21 are disconnected from the air admission valves 9 and 10 so that the closing of the air admission valves 9 and 10 does not prevent continuations of movements of the

air exhaust valves 12 and 14, while the over-travel of the air admission valves 9 and 10 in opening does not tend to restrict the port or thoroughfare areas controlled by these valves. The air admission valves 9 and 10 and the air exhaust valves 12 and 14 are illustrated by the drawing as poppet valves and their necessary lift for full opening of their ports is one-quarter of the diameters of their respective ports less the lift resulting from the partial reduction of the port areas by the rod 17 and the stems 25 and 27, but an overlift or overthrow of these valves will not tend to diminish the port areas controlled by them. The valve movements can, therefore, be entirely independent of each other as far as extent of movement is concerned, and this principle of independence of movement of these valves may be characterized as independence of seating movement, and independence of overthrow in opening movement. The constructional point to be observed is that the movements of the air exhaust valves 12 and 14 be sufficient to open the air admission valves 9 and 10 and to permit them to close, as is clearly illustrated by the drawing where the bell-crank lever 21 is shown in contact with the stem 27 of the air admission valve 10 and the bell-crank lever 20 is shown as not contacting with the stem 25 of the air admission valve 9. The reason for the construction illustrated and described is because it is customary to face the valves with a non-metallic material 28, which is clearly shown in connection with the air exhaust valves 12 and 14, to secure air tight joints when the valves are seated upon their seats. These so-called valve facings are subject to changes in volume with change of conditions so that the actual extent of movement required to seat a valve is indefinite. The construction described and illustrated permits any one of the four valves, the air admission valves 9 and 10 and the air exhaust valves, to be properly seated air tight notwithstanding the indefiniteness of the actual point of seating of any one or more of them.

A lever 29 is pivoted to the rod 17 by a pin 30 and is pivoted to the head 31 by a pivot 32. A fluid-pressure motor 33, comprising a diaphragm 34, a head 35, plunger 36, stem 37, and spring 38, is connected with the pump chamber 1 by a pipe 39 which extends below the low water level in the pump chamber 1 and has its open lower end controlled by a valve 40 which is either opened or closed by a float 41 guided by a guide 42. The pipe 39 communicates with a fluid chamber 43 between the diaphragm 34 and the head 35 so that when the float 41 opens the valve 40 water will be forced by the compressed air into the fluid chamber 43 and rock the lever 29 to shift the positions of the air exhaust valves and the air admission

valves. This shifting of the valves will place the parts in the positions shown by the drawings, that is, the lever 29 and the air admission valves and the air exhaust valves, and the spring 38 will then force the water from the fluid chamber 43 back into the chamber 1, the air pressure therein having been reduced by the opening of the air exhaust valve 12 and the closing of the air admission valve 9. A fluid-pressure motor 44, comprising a diaphragm 45, a head 46, a plunger 47, a stem 48, and spring 49, is connected with the pump chamber 2 by a pipe 50 which extends below the low water level in the pump chamber 2 and has its open lower end controlled by a valve 51 which is either opened or closed by a float 52 guided by a guide 53. The pipe 50 communicates with a fluid chamber 54 between the diaphragm 45 and the head 46 so that when the float 52 opens the valve 51 water will be forced by the compressed air into the fluid chamber 54 and rock the lever 29 to shift the positions of the air exhaust valves and the air admission valves, and the spring 49 will then force the water from the fluid chamber 54 back into the chamber 2, the air pressure therein having been reduced by the opening of the air exhaust valve 14 and the closing of the air admission valve 10. The head 46 is provided with a bleed hole 55 in the upper part thereof and the head 46 is provided with a bleed hole 56 in the upper part thereof. These bleed holes are primarily intended to prevent the motors from becoming air bound as water contains some air which tends to separate therefrom. Some water may also escape through these bleed holes but the principle of operation of the pump will not be affected provided that the bleed holes are smaller in area than the interior cross-sectional areas of the pipes 39 and 50.

The head 31 of the pump may be constructed in any suitable manner. The specific construction illustrated by the drawing includes an air chamber 57, valve chests 58 and 59, and an exhaust chamber 60. An exhaust pipe 61 may extend from the exhaust chamber 60 to a point above the surface of the water in which the pump is submerged. The valve chest 58 is connected with the pump chamber 1 by means of a pipe 62 and the valve chest 59 is connected with the pump chamber 2 by a pipe 63 so that the valve chests and the pump chambers are in function and effect the same as though they were not separated by the pipes 62 and 63, these pipes being employed as convenient features of construction in the specific construction illustrated by the drawing.

The floats 41 and 52 are provided with stems 64 and 65 which extend through holes in the guides 42 and 53 and they are also

provided with stems 66 and 67 which extend through holes in the valve levers 68 and 69, to which the valves 40 and 51 are secured, so that the floats will not open their valves until the water levels in the pump chambers have first been lowered to the lines of flotation of the floats 41 and 52, when further lowering of the water levels will result in the lowering of the floats until the float 41 contacts with the valve lever 68 and the float 52 contacts with the valve lever 69. When a float contacts with its valve lever, its valve lever will not at first be moved because the pressure in the pump chamber is sufficient to hold the valve closed against the lower end of the pipe which communicates with the motor for that chamber, but a continued lowering of the water level leaves more of the float out of the water until a point is reached where the weight of the float, in connection with the leverage of the valve lever, is sufficient to open the valve to admit water, forced by the compressed air, into the fluid chamber of the motor to reverse the positions of the air exhaust and air admission valves. The valve lever 68 is pivoted by a pivot 70 to the pipe 39 and the valve lever 69 is pivoted by a pivot 71 to the pipe 50. A head 72 on the stem 66 raises the valve lever 68 and closes the valve 40 when the float 41 rises as water fills the pump chamber 1, and a head 73 on the stem 67 raises the valve lever 69 and closes the valve 51 when the float 52 rises as water fills the pump chamber 2. The floats 41 and 52 must be light enough to float and heavy enough to open the valves 40 and 51 against the pressures in their pump chambers, taking into account, of course, the leverages exerted by the valve levers 68 and 69.

The operation of the pump is as follows. The drawing illustrates the parts in the positions which they occupy when the compressed air is exerting pressure on the water in the pump chamber 2 to expel water therefrom and when the pump chamber 1 is filling with water. The air admission valve 10 is open and the compressed air is flowing from pipe 8 into air chamber 57 and from there into the valve chest 59 and pump chamber 2. The air exhaust valve 14 is held closed because the air pressure in the valve chest 59 is greater than the pressure in the exhaust chamber 60. The valve 51 is held closed not only by the buoyancy of the float 52 but also because the pressure in the pump chamber 2 is greater than the pressure in the exhaust chamber 60. The water outlet valve 6 is open and the water is being forced from the pump chamber 2 out through the water discharge pipe 7. As the water level lowers, the surface of the water will eventually reach the line of flotation of the float 52 and, thereafter, the

float 52 will descend with the lowering water level until it rests against the valve lever 69 and its descent is arrested. The water level, however, will continue to lower until so much of the float 52 is out of water that its weight is sufficient to overcome the pressure which is holding the valve 51 closed. The float 52 then drops suddenly opening the valve 52 wide, because the pressure on opposite sides of the valve are equalized the instant that it has been opened at all. Water is now forced into the fluid chamber 54 and presses the diaphragm 45, plunger 47, stem 48 and the lower end of the lever 29 to the right, opening the exhaust valve 14, closing the exhaust valve 12 and opening the air admission valve 9, while the spring 16 closes the air admission valve 10. The air exhausts, reducing the pressure in the pump chamber 2 and the pressure of the water in the water discharge pipe 7 closes the water outlet valve 6 and the pressure of the water in which the pump is submerged opens the water inlet valve 4 and fills the pump chamber 2. The spring 49, when the pressure is reduced in the pump chamber 2, will force the water from the fluid chamber 54 back into the pump chamber 2 and restore the diaphragm 45, plunger 47 and stem 48 to the positions shown by the drawing. With the reversal of the air admission valves and the air exhaust valves, the compressed air will force the water from the pump chamber 1 through the pipe 7 until the air exhaust valves and the air admission valves are restored by the motor 33 to the positions shown by the drawing, and then the water which has filled the pump chamber 2 will be expelled, repeating the cycle of operation.

The valve levers 68 and 69 are provided with lips 74 and 75 to contact with stops 76 and 77 to limit the downward movements of these valve levers and the valves carried thereby.

The diaphragms 34 and 45 should be free to be moved by fluid pressure or by the springs 38 and 49 and one or more holes 78 and 79 may be provided communicating with the water in which the pump is submerged, and of sufficient size to permit free movements of water therethrough, so that the freedom of movement of these diaphragms and the plungers 36 and 47 will not be interfered with.

What is claimed is:

1. In a pneumatic pump, the combination with pump chambers provided with water inlet valves, water outlet valves, air admission valves and air exhaust valves, of motor mechanism for actuating the air exhaust valves, means unassociated with said air exhaust valves for closing the air admission valves, independent of connections

with the exhaust valves, and means for opening an air admission valve during a movement of the air exhaust valves.

2. In a pneumatic pump of the class described, a plurality of pump chambers, a valve chest communicating with each of said chambers, an exhaust chamber common to both said pump chambers and communicating therewith through said valve chests, valves for controlling the latter communication, an air admission chamber also common to and communicating with both said pump chambers and said valve chests, valves mounted in said admission chamber for controlling such communication, and means for actuating said valves.

3. In a pneumatic pump of the class described, a plurality of pump chambers, a valve chest communicating with each of said chambers, an exhaust chamber common to both said pump chambers and communicating therewith through said valve chests, valves for controlling the latter communication, an air admission chamber also common to and communicating with both said pump chambers and said valve chests, valves mounted in said admission chamber for controlling such communication, means for actuating said first-named valves, means interposed between said first and second-named valves for effecting actuation of the latter in one direction by means of the former, and independent means for actuating said valves of the air admission chamber in the opposite direction.

4. In a pneumatic pump of the class described, a plurality of pump chambers, a valve chest communicating with each of said chambers, an exhaust chamber common to both said pump chambers and communicating therewith through said valve chests, valves for controlling the latter communication, an air admission chamber also common to and communicating with both said pump chambers and said valve chests, valves mounted in said admission chamber for controlling such communication, means for actuating one set of said valves, means whereby the latter set operates the valves of the admission chamber in one direction, and independent means for actuating the admission chamber valves in the other direction.

5. In a pneumatic pump of the class described, a plurality of pump chambers, a

valve chest communicating with each of said chambers, an exhaust chamber mounted between said chests and communicating with the latter, valves in said chests for controlling said communication, an air admission chamber common to both said chests and provided with ports communicating therewith, valves in said chamber co-acting with said ports and having portions thereof protruding through the latter into said chests, and pivoted elements mounted in said chests and interposed between said first-named valves and the said protruding portions of said second-named valves for causing operation of the latter upon movement of the former in one direction. 70

6. In a pneumatic pump of the class described, a plurality of pump chambers, water inlet and outlet valves, air admission and air exhaust valves, said air exhaust valves being connected one with the other and said air admission valves being unconnected, motor means for actuating the exhaust valves, separate means for independently actuating each admission valve in the closing direction, and a pivoted element interposed between each exhaust and admission valve and operated by the former for causing actuation of the latter in the opening direction, said pivoted elements being loosely associated with said admission valves and capable of a certain amount of free play so as not to interfere with the proper seating of said valves as the latter become worn. 80

7. In a pneumatic pump of the class described, a plurality of pump chambers, a valve chest communicating with each of said chambers, an exhaust chamber common to both of said pump chambers and communicating therewith through said valve chests, valves for controlling the latter communication, an air admission chamber also common to and communicating with both said pump chambers and said valve chests and overlying the latter across the top of said pump, valves mounted in said admission chamber for controlling such communication, and means for actuating said valves, said admission chamber being provided with an opening in the top wall thereof affording access to said valves. 100

In witness whereof I hereto affix my signature.

HOMER S. ROGERS.
